UNITED STATES PATENT OFFICE.

FRANK MOSSBERG, OF ATTLEBORO, MASSACHUSETTS, ASSIGNOR TO MOSSBERG
PRESSED STEEL CORPORATION, OF ATTLEBORO, MASSACHUSETTS, A CORPORA-
TION OF MASSACHUSETTS.

REEL.

Application filed January 18, 1924. Serial No. 687,028.

This invention relates to improvements in the construction of annealing or stranding reels and the like, and the method of forming the same: and the object of this invention is to provide such a reel having its body and head-plates welded together.

A further object of this invention is to provide an annealing reel which will be light in construction and yet will be durable to 10 withstand the continuous heating in an annealing furnace and subsequent cooling.

With these and other objects in view, the invention consists of certain novel features of construction, as will be more fully 15 described, and particularly pointed out in the appended claims.

In the accompanying drawings:

Figure 1 is a side elevation partly in section showing the annealing reel embodying 20 my improved construction.

Figure 2 is a sectional elevation illustrating the spacing of the tubular body portion from the head-plates and the welding operation.

25 Figure 3 is an end view of Figure 2 with one of the head-plates removed or on line 3—3 of Figure 2, looking in the direction of the arrow.

Figure 4 is an enlarged detail showing the 30 spacing element between the end of the tubular body portion and the head plate.

Figure 5 is a sectional elevation showing a reel welded from the inside.

35 Figure 6 is an enlarged portion showing one form of joint between the body portion and the head-plate before the stock at the juncture has been affected by the welding operation.

It has been found in practice that annealing or stranding reels on which wire is to be wound to be annealed and which have their heads and body portions riveted together, become loosened from each other and are no longer suitable for use after having been 40 subjected a number of times to the intense heating and subsequent cooling actions necessarily employed for the annealing of the wire due to excessive expansion and contraction. It is also found that when such 45 reels are assembled by rivets they must be formed of comparatively heavy material which absorbs and wastes more heat than one formed of a lighter weight also one of such heavy weight also increases the strain due to 50

centrifugal force when they are rapidly 55 rotated in a stranding machine for forming the wire into cables, and it is found that by providing a reel of sheet metal and welding the heads and body portions together that the entire reel is formed substantially homo- 60 geneous without rivets or bolts to loosen as result of the excessive expanding and contracting actions due to the intense heating and cooling, and that the parts when so welded together may be made of much thinner and lighter material which again serves to reduce the centrifugal strains present during the rapid rotations while in the stranding machine; and the following is a detailed 65 description of one construction of my im- 70 proved reel:—

With reference to the drawing, 10 designates the head-plates which are disc-shaped and may be of any desired material but as here illustrated are of sheet metal, and each of these head-plates is preferably provided with a central opening 11. Between the head-plates in concentric relation to this opening, I have mounted a body portion 12 constructed of any suitable material but which is preferably cut from sheet stock such as steel and the like and rolled into tubular form having its abutting edges 13 welded together and having its ends securely welded to the inner surfaces of the head-plates by a 75 ring 14 of fused metal, whereby the body portion and the two head plates are secured together forming a substantial homogeneous 80 structure or device.

In some instances, I also provide a tubular core 15 of any suitable material, which is secured to the edges of the opening 11 in each of the head-plates.

Also in some instances, I find it convenient and desirable to form a hub portion or a centrally located outward projection 16 on each of the head-plates, as illustrated in Figure 1, which may serve to stiffen the same, while in order to reduce the weight of the annealing reel so that will absorb the minimum amount of heat from the annealing furnace, I remove the unnecessary portion of the discs by forming a plurality of holes 17 adjacent the outer periphery of the head-plates.

I have found that it is often desirable to 105 remove a portion of the stock at the joint, either in the head or in the body portion, to permit the fused welding material to

flow thereinto to form a joint of the required strength, and I may accomplish this by beveling or chamfering the end of the body portion to expose a greater adhering surface to the welding material and so provide a stronger joint. In still other instances, it is found desirable to hold the body portion and the head in spaced relation by means of small pieces of stock or material 10 placed about the edges of the body portion between the body and the head-plates 12 and by applying the welding material to these joints while held in this spaced relation the metal flows into this space and 15 affords a greater adhering surface to the welding material and provides a method by which the welding material may be applied in greater quantities to more securely hold the body and head-plates in their desired relation. In still other instances, I have found that even though the head-plates are in contact with the end of the body the flowing of welding material about the junction fuses a portion of the stock at the joint 20 which unites with the welding material and also increases the adhering surfaces of the parts at the joint for the adhering of welding material.

In some instances, where extremely fine wire is desired to be wound upon the annealing reel, I wish to eliminate the fillet of welding material which fills in the joint and prevents a sharp, right-angular corner between the head-plates and body portion, 30 and in order to avoid this fillet in reels adapted for use with small wire, I apply the welding material about the inner peripheral surface of the body portion as shown at 21, in Figure 5, which leaves a 35 right-angular connection between the body portion and head-plates. It is also found that the welding material readily pockets on the inner edge of the body portion thus providing an extended adhering surface for 40 rigidly securing the body and head together.

In order to secure the wire wound on the annealing reel, I provide a hole 22 adjacent the junction of the head plates and body for securing the starting end of the wire and a 50 hole 23 located about the periphery of one of the plates for securing the finishing end of the wire to the reel.

By my improved construction of annealing or stranding reels, I have provided a 55 reel of maximum strength and of minimum weight which is substantially homogeneous in construction and which will withstand a considerable amount of heating and cooling without perceptible deterioration and which 60 absorbs only the minimum amount of heat from the annealing furnace and which possesses many advantages over the old style riveted heads of a heavier and more expensive construction.

65 Having thus described one illustrative em-

bodiment of my invention and the best mode known to me for carrying out my method, I desire it to be understood that although specific terms are employed, they are used in a generic and descriptive sense and not for 70 the purpose of limitation, the scope of the invention being defined and limited only by the terms of the appended claims.

I claim:

1. A sheet metal annealing reel comprising a tubular body member having a head-plate member at each end thereof of a stock substantially twice as thick as that of the body member, the ends of the body member being adjacent the inner surface of the head-plate members, and additional metal fused and deposited in a continuous ring at the juncture to form a fillet and unite said members together as a homogeneous assembly of parts. 75

2. A sheet metal annealing reel comprising a tubular body member having a head-plate member at each end thereof of a stock heavier than that of the body member, the ends of the body member abutting the inner surface of the head-plate members, a portion of the stock at the junction of said members being removed to form a recess at the junction, and metal fused and deposited in a continuous ring at the juncture to unite said members together as a homogeneous assembly of parts. 80

3. A sheet metal reel comprising a tubular body member, head-plate members of stock of a thickness greater than that of the stock of the body member and having a central opening therethrough smaller than the diameter of said body member, said plates being adjacent each end of the body member, and an additional ring of fused metal between said head and body members forming a fillet at their juncture and uniting said members as a homogeneous assembly of parts. 100

4. A sheet metal reel comprising a tubular body member having a head-plate member at each end thereof of a stock heavier than that of the body member the ends of the body being adjacent the face of the head plate and having a continuous homogeneous fillet of metal fused and deposited at the junction of the body and heads forming a joint with a sectional area greater than that of any similar section through the body intermediate its ends. 110

5. A method of forming a reel, which consists in providing head-plates, forming a sheet of metal of a thickness less than the head-plates into a tubular body of a diameter less than the head plates, positioning said body between said head-plates with the ends of the body adjacent and substantially perpendicular to said head plates, and adding a fillet of fused metal between the ends of said body and said head-plates 115 120 125 130

to weld the two together and provide a homogeneous assembly of parts.

6. A method of forming a wire reel, which consists in providing head-plates, forming a sheet of metal into a tubular body of a diameter less than the head-plates, positioning said body between said plates abutting the inner surface thereof, fusing and flowing a portion of the stock at the junction of the body and plates, and 10 flowing welding material into the space formed by the fused and flowed portion to provide a homogeneous assembly of parts.

In testimony whereof I affix my signature.

FRANK MOSSBERG.
